O. CROSBY

DIPPER TOOTH POINT FOR EXCAVATING SHOVELS

Filed Oct. 22, 1921

Patented June 30, 1925.

1,544,222

UNITED STATES PATENT OFFICE.

OLIVER CROSBY, OF ST. PAUL, MINNESOTA, ASSIGNOR TO AMERICAN HOIST & DERRICK CO., OF ST. PAUL, MINNESOTA, A PARTNERSHIP.

DIPPER-TOOTH POINT FOR EXCAVATING SHOVELS.

Application filed October 22, 1921. Serial No. 509,542.

To all whom it may concern:

Be it known that I, OLIVER CROSBY, a citizen of the United States, resident of St. Paul, county of Ramsey, State of Minnesota, have invented certain new and useful Improvements in Dipper-Tooth Points for Excavating Shovels, of which the following is a specification.

The object of my invention is to provide a dipper tooth point adapted to be rigidly mounted on the end of the tooth shank and capable of quick detachment for renewal or repairs.

A further object is to provide a detachable point of such construction and secured in such a way that it will form practically an integral part of the tooth when the excavating shovel is in use.

Other objects of the invention will appear from the following detailed description.

The invention consists generally in various constructions and combinations, all as hereinafter described and particularly pointed out in the claims.

In the accompanying drawings forming part of this specification,

Figure 1 is a perspective view of the forward portion of a dipper tooth, showing my removable point mounted thereon.

Figure 2 is a perspective view of the point removed from the shank of the tooth.

Figure 3 is a perspective view of the forward end of the tooth, with the point removed.

Figure 4 is a sectional view on the line 4-4 of Figure 1.

Figure 5 is a plan view of the point showing, somewhat exaggerated, the taper of the tongue on the point.

Figure 6 is a similar view of the underside of the tooth, showing, somewhat exaggerated, the taper socket adapted to receive the tongue on the point.

Figure 7 is a sectional view on the line 7-7 of Figure 5.

In the drawing the numeral 2 designates the shank of the dipper tooth formed with the usual recess 3 to receive the edge of the dipper in the usual manner of affixing teeth thereto. The dipper will be provided with a series of these shanks projecting in front thereof and having points adapted to dig into the earth in filling the excavating dipper. Under the present invention the removable point, designated by the numeral 4,

has a beveled or curved top face 5 which will form a continuation of the upper curved face 6 of the shank, and thus the forward portion of the tooth will slide easily through the earth or soil in gathering up the load, and at its forward end one face of the point is slightly concave as indicated at 7 and will merge into the aligning face 8 of the shank as illustrated in Figure 1 of the drawing. One face of the point is cut-away or recessed as illustrated in Figures 1 and 2 so as to form an upwardly inclined face 9 on the opposite side of the upper rear portion of the face 5 as illustrated in Figures 1 and 2, and extending centrally of the inclined face 9, and longitudinally thereof, is a tongue 10 having a head 11 with side extensions 12, so as to form a T shaped tongue. At the lower extremity of this tongue, extending from one side of the tooth to the other, there is formed a shoulder 15 which lies in a plane below the tongue, and at each side of the tongue the point is formed with a shoulder 14 which is made with an upwardly inclined face that terminates in an upright wall 16 that merges into the inclined face 9 of the upper rear portion of the tooth point as illustrated in Figures 1 and 2. The sides of the T shaped tongue taper from its lower to its upper end and its end is beveled as at 13, as illustrated in Figure 5.

The forward end of the shank 2 is recessed to form an upper downwardly inclined face 18 at the upper end of which is a beveled overhanging ledge 19 to receive the beveled edge 17 of the rear upper portion of the tooth point when assembled, as shown in Figure 1. In the inclined face 18 there is formed a longitudinally extending socket 20, the confronting walls of which taper from one end to the other as shown in Figure 6 and are formed with grooves or guideways 21 which serve to receive the side extensions or ledges 12 of the T shaped tongue of the removable point when the parts are assembled, as illustrated in Figure 4. Projecting from the lower end of the inclined face 18 of the shank 2, at each side of the socket 20, are lugs 22 which have faces 23 to abut against the upright walls 16 of the removable point, and rearwardly and downwardly inclined faces 24 to rest upon the inclined faces of the shoulders 14, and a downwardly extending shoulder 25 to abut

against the shoulder 15 of the removable point when the shank and removable point are assembled as shown in Figure 1.

It will be observed from the construction 5 described that the removable point and shank may be readily attached one to the other, and that longitudinal and transverse and vertical stresses are readily taken up or absorbed by the bracing effect afforded by 10 one to the other. There are no oppositely diverging wings or arms to either the removable point or shank and consequently greater stability and strength and less liability to breakage are results attained, and 15 the two parts when assembled have practically the strength as if made in one integral piece while possessing the advantage that the tooth may be readily detached and replaced by another when necessary. The T 20 shaped tongue and groove connection between the point and shank has the advantage over a dovetailed connection that it is not as liable to split the metal as a dovetail connection; and the longitudinal axis of the 25 joint made by the T head and groove connection is not parallel to the wearing line of the point but transversely thereto and the joint formed by the particular construction affords all possible strength and resist 30 ing power without detracting from the easy separation of the parts when necessary. When the locking bolt further on described is removed, the enlargement around the bolt opening affords a bearing to receive the 35 end of an implement to which blows are imparted for separation of the point from the shank which often times is made difficult by reason of the joint becoming corroded when no adequate abutment is provided to receive the blows for separation of 40 the parts.

To prevent premature separation of these parts, I prefer to provide a socket 26 in the tongue 10 extending vertically through the 45 point, adapted to register with a recess 27 in the forward portion of the shank. A bolt 28 fits into this recess and socket and has a nut 29 within a recess 30 in the underside of the point. By this means the 50 point of the tooth is made renewable and can be made of very hard material to resist wear when the tooth passes through gravel and rough material. All of the 55 wear on a tooth practically takes place at the point and when this point changes shape by wear, the teeth and dipper do not satisfactorily penetrate the material to be shoveled. The point being hard and easily renewed enables a dipper to be quickly and 60 cheaply repaired without the necessity of re-

moving the main part of the shank 2, which is riveted or bolted to the front nose of the dipper. The main shank 2 wears slowly and can be made of a softer material than the point.

65

I claim as my invention:

1. An excavator dipper-tooth comprising a detachable point provided with an overhanging member having an upwardly inclined inner face, a substantially T-shaped tongue projecting from the under side of the inclined face, a shoulder at the lower extremity of the tongue extending transversely of the tooth, and shoulders at opposite sides of the tongue, each formed with an inclined seating face terminating in an upright wall intersecting the inclined face of the overhanging member; and a shank formed with an inclined face having a substantially T-shaped longitudinally extending 70 socket to receive the T-shaped tongue of the point and a transversely extending shoulder to bear against the transversely extending shoulder of the point and formed at opposite sides of the socket with forwardly 75 projecting lugs having inclined faces to seat upon the inclined faces of the side shoulders of the point and with end portions to abut the upright walls of said shoulders.

80

2. An excavator dipper tooth comprising 90 a detachable point formed with a recess extending throughout a portion of its length to provide an overhanging member having an upwardly inclined inner face and a beveled terminal edge, a substantially T shaped 95 tongue projecting from the under side of the inclined face, a shoulder at the base of the tongue extending from side to side of the tooth, and shoulders at opposite sides of the tongue, at its base, each formed with 100 an inclined seating face terminating in an upright wall intersecting the inclined face of the overhanging member; and a shank formed with an inclined face terminating in a beveled recess to receive the beveled edge 105 of the point and formed with a substantially T shaped longitudinally extending socket to receive the tongue of the point, the shank being provided with projecting end lugs at 110 opposite sides of the socket formed with upright end faces to bear against the upright walls of the side shoulders of the point and with inclined faces to seat on the inclined faces of the said shoulders and having a transversely extending shoulder to fit 115 against the transversely extending shoulder of the point.
